CLAIM

The ornamental design for a voice interface device, as shown and described.

DESCRIPTION

FIG. 1 is a front left 3/4 view of a voice interface device showing the new design.

FIG. 2 is a front view of the voice interface device shown in FIG. 1.

FIG. 3 is a rear view of the voice interface device shown in FIG. 1.

FIG. 4 is a right side view of the voice interface device shown in FIG. 1.

FIG. 5 is a top view of the voice interface device shown in FIG. 1; and,

FIG. 6 is a bottom view of the voice interface device shown in FIG. 1.

(Continued)

The broken lines showing elements of the voice interface device in the above described figures are for illustrative purposes only and form no part of the claimed design.

1 Claim, 6 Drawing Sheets
